(57) **CLAIM**

The ornamental design for a wall frame corner component, as shown and described.

DESCRIPTION

FIG. 1 is a top front perspective view of a first embodiment of a wall frame corner component showing my new design; FIG. 2 is a top back perspective of the wall frame corner component of FIG. 1;

FIG. 3 is a bottom perspective view of the wall frame corner component of FIG. 1;

FIG. 4 is a top plan view of the wall frame corner component of FIG. 1;

FIG. 5 is a bottom plan view of the wall frame corner component of FIG. 1;

FIG. 6 is a front elevation view of the wall frame corner component of FIG. 1;

FIG. 7 is a right side elevation view of the wall frame corner component of FIG. 1;

FIG. 8 is a back elevation view of the wall frame corner component of FIG. 1;

FIG. 9 is a left side elevation view of the wall frame corner component of FIG. 1;

FIG. 10 is a top front perspective view of a second embodiment of a wall frame corner component showing my new design;

FIG. 11 is a top back perspective of the wall frame corner component of FIG. 10;

FIG. 12 is a bottom perspective view of the wall frame corner component of FIG. 10;

FIG. 13 is a top plan view of the wall frame corner component of FIG. 10;

FIG. 14 is a bottom plan view of the wall frame corner component of FIG. 10;

(Continued)

FIG. 15 is a front elevation view of the wall frame corner component of FIG. 10;
 FIG. 16 is a right side elevation view of the wall frame corner component of FIG. 10;
 FIG. 17 is a back elevation view of the wall frame corner component of FIG. 10; and,
 FIG. 18 is a left side elevation view of the wall frame corner component of FIG. 10.
